DESIGN FOR A DRIP CATCHER

Ada May, New York, N. Y.

Application December 8, 1939, Serial No. 88,760

Term of patent 7 years

To all whom it may concern:

Be it known that I, Ada May, a citizen of the United States and a resident of the city of New York, in the county of New York and State of New York, have invented a new, original, and ornamental Design for a Drip Catcher, of which the following is a specification, reference being had to the accompanying drawing, forming a part thereof.

Fig. 1 is a perspective view of a drip catcher, showing my design;

Fig. 2 is a front elevational view thereof, the cord being shown broken away; and

Fig. 3 is a side elevational view of the head element shown in Fig. 2, the cord being shown broken away.

I claim:

The ornamental design for a drip catcher, substantially as shown.

ADA MAY.
